No. 792,507.

PATENTED JUNE 13, 1905.

C. L. DUNDEY.
CAR COUPLING.

UNITED STATES PATENT OFFICE.

CHARLES L. DUNDEY, OF OMAHA, NEBRASKA.

CAR-CO尤LING.

SPECIFICATION forming part of Letters Patent No. 792,507, dated June 13, 1905.

Application filed February 28, 1905. Serial No. 247,728.

To all whom it may concern:

Be it known that I, CHARLES L. DUNDEY, a citizen of the United States, residing at Omaha, in the county of Douglas and State of Nebraska, have invented certain new and useful Improvements in Car-Couplers; and I do hereby declare the following to be a full, clear, and exact description of the invention, such as will enable others skilled in the art to which it applies to make and use the same.

This invention relates to improvements in automatic car-couplers, and more particularly to means for throwing a knuckle of a coupler to an open condition and for maintaining the same in such condition.

The object in view is the provision of means applicable to any of the couplers now on the market for automatically opening a knuckle and maintaining the same in an open condition.

Referring to the drawings, Figure 1 represents a top plan view of a coupler embodying the features of the present invention, parts being broken away for disclosing interior structure and the knuckle being shown in its closed condition. Fig. 2 represents a similar view of the same with the knuckle in its open condition. Fig. 3 represents a detailed fragmentary view illustrating a modified form of the present improved car-coupler. Fig. 4 represents a detailed fragmentary view illustrating a further modification.

This invention involves a spring for throwing the knuckle to an open condition when released, and I wish it understood that I am aware that various attempts have been made to provide a spring designed for this purpose and that, as far as I am aware, the use of springs heretofore has not been found practicable. In order to produce a practical construction which is applicable to any of the couplers now on the market and which will not require any great modification for its adoption, I propose to employ a structure embodying the invention disclosed in the accompanying drawings, in which—

1 indicates an ordinary type of automatic car-coupler head, and 2 the coupler-pin therefor. To the head 1 is pivoted the usual knuckle 3, provided with the ordinary tailpiece 4.

The elements mentioned thus far are all old and well known and may be of any preferred type, it being common to arrange the pin 2 in such position as to automatically drop when the knuckle is closed to a position for locking the knuckle in such closed condition. To this construction I propose to add means for throwing the knuckle to an open position when the pin 2 is raised and for maintaining the same in such open position under ordinary circumstances, such means consisting in the provision of a spring 5 of the conical type positioned with its base resting against the tailpiece 4 and connected therewith in any desired manner, a very slight recess 6 being preferably provided for receiving such base. The apex of the spring 5 extends toward the casing of the head 1, and said casing is preferably apertured, as at 7, through which aperture extends the rod 8, formed of and projecting from the apex end of the spring 5, such rod 8 being threaded and provided with a nut 9, engaging the inner surface of the casing of head 1 for preventing outward movement of the spring, and a plate 10 being mounted on the projecting end of the rod 8 outside the casing and the nut 11 being threaded onto the projecting end of the rod 8 for retaining the parts against movement. Of course a suitable cotter 12 may be passed through the projecting end of the rod 8 for preventing displacement of the nut 11, or any suitable means may be provided for locking the nut against movement.

As seen in Fig. 3, the nut 11 and plate 10 may be omitted and a cotter 13 may be employed for retaining the parts in position.

The spring 5, while described and illustrated as conical, is in addition in the nature of a volute spring, except that the spring is preferably not made flat, although of course a flat spring might be employed, the chief object in making the spring conical being to provide for the spring assuming a very compact condition, as illustrated in Fig. 1, the spring when compact having its various laps folded, each within the next larger, so that the recess 6 may be very shallow, indeed, and if any space exists between the casing of the head 1 and tailpiece 4 no recess is necessary at all.

It will be observed that by the use of this particular form of spring all the advantages obtained from the use of a spring for throwing the knuckle to an open condition are secured, while the disadvantages of weakening the parts, altering the construction of the head, or exposing the spring to the action of the elements are not met with. It will be observed, of course, that by providing the spring 5 when the pin 2 is raised for releasing the knuckle 3 the knuckle will be thrown from the spring from the position illustrated in Fig. 1 to the position illustrated in Fig. 3, and the knuckle 3 will be held in such position regardless 10 of jarring to which the knuckle may be subjected during shifting of the car to which the coupler is connected. Of course when a second coupler is brought to a position for having the knuckle strike the tailpiece of the 15 knuckle 3 the same will swing readily to its closed position and permit the pin 2 to drop to a locking position.

As seen in Fig. 4, it is possible to reverse the position of the spring, the spring 5', (illustrated in said figure,) being positioned with its apex contacting with the tailpiece of the knuckle and its base resting against the casting of the coupler-head. The end of the rod constituting the spring may be extended from 20 the base through the wall of the head, as illustrated in Fig. 4, or the spring may be secured in position in any preferred manner.

The particular construction of spring above described is in the nature of a volute spring

which acts longitudinally—that is to say, the 5 spring acts at right angles to the plane of its coils, and the movement of the spring when released is in the nature of a longitudinal thrust.

What I claim is—

1. In a car-coupler, the combination with a head, a knuckle pivoted thereto, and a tail-piece carried by said knuckle, of a longitudinally-acting volute spring interposed between said tailpiece and head for throwing the tail-piece outward when released. 40

2. In a coupler, the combination with a head, and a knuckle pivotally connected thereto, of a conical spring interposed between said knuckle and said head for maintaining 45 the knuckle in an open condition when released, the larger coils of said spring being designed to inclose the smaller coils thereof when compressed. 50

3. In a coupler, the combination of a head, and a knuckle pivotally connected thereto, of a conical spring interposed between said head and knuckle, and having its base contacting with the knuckle and its apex extended toward said head, the smaller coils of said spring 55 being designed to be inclosed by the larger coils thereof when compressed. 60

In testimony whereof I hereunto affix my signature in presence of two witnesses.

CHARLES L. DUNDEY.
